UNITED STATES PATENT OFFICE.

JOSEPH E. KENNEDY, OF NEW YORK, N. Y.

GYRATORY CRUSHING APPARATUS.

1,295,757.

Specification of Letters Patent. Patented Feb. 25, 1919.

Original application filed October 23, 1917, Serial No. 198,023. Divided and this application filed January 14, 1918, Serial No. 211,712.

To all whom it may concern:

Be it known that I, JOSEPH E. KENNEDY, a citizen of the United States, and a resident of the borough of Manhattan, city, county, and State of New York, have invented certain new and useful Improvements in Gyratory Crushing Apparatus, of which the following is a specification.

The present application is a division of that filed by me Oct. 23, 1917, Serial No. 198,023, and relates more particularly to the means provided for the lubrication of the eccentric bearing in which the lower part of the gyratory shaft is mounted,—the invention consisting in the specific construction and arrangement of parts described and claimed, and a distinctive feature being the method whereby a forced circulation of the lubricant is positively and automatically attained, and a supply thereof to the top of the bearing assured, all as hereinafter more fully set forth.

The accompanying drawing is a central vertical sectional elevation of a gyratory crushing apparatus to which my lubricating system is applied.

In general characteristics the apparatus illustrated in the drawings is primarily the same in principle and operation as set forth in Letters Patent No. 1,085,867, issued to me Feb. 3, 1914, No. 1,090,216, issued to me March 17, 1914, and No. 1,176,833, issued to me March 26, 1916, to which reference may be had as showing the type of gyratory crusher to which my present improvements are especially applicable. Thus the truncated conical crushing head *a*, is rigidly secured to the shaft *A*, and is gyrated thereby within a concave crushing chamber *b*, from the lower portion of which the reduced material drops into the chute chamber *d*, in the usual manner.

The shaft *A*, is suspended on an inclosed top or cover *C*, of special construction, having a central hub *c*, formed with an integral bottom flange or annular shoulder *c'*, on which the said shaft *A*, is fulcrumed in such manner as to allow of its gyration by means of the eccentric bearing *e*, in which the lower end of said shaft *A*, is mounted. The upper extremity of the shaft *A*, is screw threaded and provided with a nut collar *a'*, which bears on a sleeve *a''*, resting in turn on a gasket *a'''*, interposed between it and said annular shoulder *c'*, of the hub *c*,

of the cap plate *C*, as shown in the drawings,—a bushing *c''*, being interposed between the hub *c*, and the bearing sleeve *a''*.

To the upper part of this eccentric bearing sleeve *e'*, is rigidly secured, as by the key *e''*, to the driven pulley *e'''*, by which said sleeve *e'*, is rotated to impart a gyratory rotation to the shaft *A*, through the medium of the aforesaid eccentric bearing *e*, the operation and functions of which latter are clearly set forth in the Letters Patent hereinbefore referred to, particularly Letters Patent No. 1,176,833, the means for effecting the lubricating circulation being essentially the same as disclosed in that patent except that in the present case I supplement the automatic system of lubrication by positive means for transferring the lubricant from the exterior of the rotatable sleeve *e'*, to the interior thereof. The sleeve *e'*, is formed with an annular flange *e''*, by which it is rotatably supported on the lower casing or bottom plate *g*,—a floating ring *e'''*, being interposed between said annular flange *e''*, and the actual rest or seat *g'*. Surrounding the seat *g'*, is an annular gutter *g''*, to receive the oil which passes out around the floating ring *e'''*. The bottom of this annular gutter *g''*, is inclined as indicated by the dotted line *g'''*, to conduct the oil thus received into a pocket *g'''*, from which the oil is returned in part through the duct *g''*, to the space in the casing below the shaft, bearing, and sleeve, to again percolate upward by capillary attraction between the opposed surfaces to be lubricated, as set forth in said Letters Patent No. 1,176,833. The rotation of the parts thus insures an automatic circulation of the oil which is most effective for their lubrication.

In order however to positively insure a supply of lubricating oil to the sleeve *e'*, above the eccentric bearing *e*, and thereby effect a gravity feed to said bearing *e*, to supplement the upward capillary feed to the annular gutter *g''*, I abstract a portion of the oil from the pocket *g''''*, by means of the pipe *p*, leading to the pump *P*, by which it is returned by the pipe *p'*, through the filter *p''*, to the sleeve *e'*, as indicated in the drawing. This utilization and combination of both capillary and gravity attraction obviates all danger of injury from lack of lubrication through failure of ample supply of oil to the contracting surfaces

and safeguards the apparatus in this respect against carelessness or indifference on the part of attendants.

The force pump P , is driven by motion 6 derived from an operative part, as by a belt p^3 , passing around a drive pulley p^4 , attached to the pump P , and around a groove formed for it in the upper part of the bearing sleeve e' . The upper end of the latter 10 is closed by a dust guard h ; and the inlet pipe p' , from the pump P , may enter the said sleeve e' through said dust guard h , as shown. h' , is a dust guard which closes the opening in the upper part of the drive 15 chamber in the usual manner.

What I claim as my invention and desire to secure by Letters Patent is,

1. In crushing apparatus of the character designated, the combination with the gyro- 20 tory shaft, eccentric bearing, rotatable sleeve, and casing therefor formed with an annular gutter for the collection of oil raised by capillary attraction and with a return conduit connecting said annular gutter with the 25 lower part of the casing, of means connected with said return conduit for positively transferring oil therefrom to the eccentric sleeve above the eccentric bearing, for the purpose described.

30 2. In crushing apparatus of the character designated, the combination with the gyro- tory shaft, eccentric bearing, rotatable sleeve, and casing therefor formed with an annular gutter for the collection of oil raised by capillary attraction and with a return conduit connecting said annular gutter with the lower part of the casing, of means connected with the casing for positively transferring oil therefrom to the eccentric sleeve above 35 the eccentric bearing, for the purpose described.

3. In crushing apparatus of the character designated, the combination with the gyro- 40 tory shaft, eccentric bearing, rotatable sleeve, and casing therefor formed with an annular gutter for the collection of oil raised by cap-

illary attraction and with a return conduit connecting said annular gutter with the lower part of the casing, of means connected with the casing for positively transferring oil therefrom to the eccentric sleeve above the eccentric bearing, said means including a pump operated by motion derived from the said rotatable eccentric sleeve, for the purpose described. 50

4. In crushing apparatus of the character designated, the combination with the gyro- 55 tory shaft, eccentric bearing, rotatable sleeve, and casing therefor formed with an annular gutter for the collection of oil raised by capillary attraction and with a return conduit connecting said annular gutter with the lower part of the casing, of means connected with the casing for positively transferring oil therefrom to the eccentric sleeve above 60 the eccentric bearing, said means comprising suitable piping, a pump interposed therein and operated by a pulley, and an endless belt driving said pulley and pump by motion derived from the rotatable eccentric sleeve, for the purpose described. 65

5. In crushing apparatus of the character

designated, the combination with the gyro- 70 tory shaft, eccentric bearing, rotatable sleeve, and casing therefor formed with an annular gutter for the collection of oil raised by capillary attraction and with a return conduit connecting said annular gutter with the lower part of the casing, of means connected with the casing for positively transferring oil therefrom to the eccentric sleeve above 75 the eccentric bearing, said means comprising suitable piping, a filter interposed in said piping and operated by a pulley, and an endless belt driving said pump and pulley by motion derived from the rotatable eccentric sleeve, for the purpose described. 80
